John Golden
Letters Patent

The Schedule referred to in these Letters Patent and making part of the same containing a description in the words of the said John Golden himself of his improvement in the art of Public finance in loaning and actually employing credit

Scall to whom these presents shall come. Be it known that John Golden of the City of Philadelphia and State of Pennsylvania have invented and formed a new and valuable accumulative or interest bearing check or credit chart based upon a principle in money negotiations and to be used as a use of improvement in the art of finance to be used only in the negotiations of loans upon contract with actual capitalists or in guarantee or transfers of bank note deposits and investments to be made a full and exact description of which is in progress and drawing thereof as invented and written by me and hereafter is designed to be used as aforesaid only specifying the names, sums, dates, and vignets which are at all times to be written and filled up in ^{the} own proper hand writing of the person or persons concerned conformable to the contracts made or to be made with the party or parties contracting therfor as hereunto annexed and the inventor and author claims as his invention not only the design and writing of the chart or check above described and attached hereto according to the specific form and definite advantages of creating and sustaining credit upon its peculiar solid principle of accumulative action and the right and privilege of using it as an improvement in negotiation of loans and investments of capital upon permanent visible security but also the operative principle upon which it is based which will admit of numerous variations in the form or manner of lending or contracting, the same whilst the principle upon which it is intended to operate will remain substantially the same and would be therefore necessarily considered as an evolution of my right.
